UNITED STATES PATENT OFFICE

2,420,367

FLUFFING UP ARTIFICIAL STAPLE FIBERS

Norma Blanche Geer, Los Angeles, Calif., and Louis William Schatz, South Tacoma, Wash., assignors to Celanese Corporation of America, a corporation of Delaware

Application November 9, 1943, Serial No. 509,636

2 Claims. (Cl. 19—96)

1

This invention relates to the treatment of staple fibers, and relates more particularly to the treatment of artificial staple fibers to open and fluff up the same whereby they become more amenable to textile operations and more adaptable to certain uses.

It is an object of this invention to provide a novel process for opening and fluffing up staple fibers having a basis of artificial material.

Another object of this invention is the provision of means for opening and fluffing up artificial staple fibers in a simple, expeditious and economical manner.

A further object of this invention is the provision of apparatus for opening and fluffing up artificial staple fiber and for filling therewith pillows, comforters, sleeping bags and the like.

Still another object of this invention is to provide a novel filling for pillows, comforters, sleeping bags and the like, which has many advantages over down-feathers, cotton and other fillings heretofore employed.

Other objects of this invention, together with certain details of construction and combinations of parts of apparatus, will appear from the following detailed description.

In the preparation of artificial staple fiber, bundles of continuous filaments are led to a cutting device where they are cut into shorter bundles. The apparent adhesion existing between the continuous artificial filaments also exists between the fibers in the shorter bundles. The mass of fiber produced by the cutting of the bundles of continuous filaments contains a large proportion of bundles or pencils of fibers, necessitating further treatment of the mass of fiber in order to make the fibers suitable for use in textile operations, such as, for instance, in the spinning of yarn therefrom. Further treatment is particularly necessary to make the staple fiber suitable for use as a substitute for down-feathers and like fillings in pillows, comforters, sleeping bags and the like. Many expedients have been employed for opening the bundles of fibers, substantially all using a fluid stream. While a stream of air or water assisted to some extent in separating the fibers, there was no fluffing up of the same.

We have now found that staple fiber may not only be opened but also fluffed up by subjecting compact bundles thereof to the action of a rotary drum having on the surface thereof pins or nails and operating in a box or bin. In the opened and fluffed up condition, the staple fibers are readily built up into a lap by the usual meth-

2

ods in the preparation of spun yarn. However, it is of greater advantage as filling in pillows, comforters, sleeping bags and the like. Accordingly, we provide means for taking the opened and fluffed up fibers from the bin and for stuffing the same into suitable fabric containers.

Cellulose derivative filaments or fibers, such as cellulose acetate filaments or fibers, are particularly prone to electrification engendered by friction, such as the friction caused by the action of the pin-studded rotary drum in the fluffing bin in which it is contained. The static charge on the fibers causes them to cling tenaciously to the bin walls thus preventing satisfactory operation of the apparatus. This difficulty is avoided by lining the fluffing bin with sheeting of metal, such as copper, and suitably grounding the sheeting. This construction of the fluffing bin obviates the necessity of treating the fibers prior to the opening and fluffing up operation with an anti-static finish. However, an anti-static finish may be applied to the bundles of fibers if it is so desired. A suitable anti-static finish comprises 100 parts of diethylene glycol, 30 parts of water and 10 parts of magnesium chloride. Other anti-static finishes may, of course, be employed. The finish is preferably applied to the filaments, in any suitable manner, prior to the cutting thereof into short or staple lengths.

The device of our invention will now be described in greater detail with reference to the accompanying drawings in which

Figure 1 is a side elevational view of apparatus embodying our invention,

Figure 2 is a partial top plan view of the apparatus shown in Figure 1, and

Figure 3 is a view of a sleeping bag in which the staple fiber opened and fluffed up by the apparatus of our invention is adapted to be used as a filling.

Like reference numerals indicate like parts throughout the views of the drawings.

Referring now to the drawings, and particularly to Figures 1 and 2, the reference numeral 4 indicates a hopper for holding bundles or pencils of staple fibers 5 as received from a cutting machine, and for feeding them on to an endless belt 6. For certain purposes, as will appear hereinafter, it is desirable to feed predetermined quantities of staple fibers and to this end the hopper 4 may be provided with an automatic weighing attachment which is more or less diagrammatically shown and generally indicated by reference numeral 7.

The endless belt operates in a substantially closed compartment 8 mounted on framework 9 of the apparatus, and is rotatably carried on idler pulley 11 and driven pulley 12. Access is had to the compartment by means of a trap door 13 attached by means of hinges 14. The trap door may be provided with a handle or knob 15. To drive pulley 12 the shaft 16 on which said pulley is mounted is provided with a sprocket 17 which is connected by means of an articulated chain 18 to a sprocket 19 mounted on shaft 21 held in brackets 22 fixed to frame 9. The shaft 21 also has fixed thereto a grooved pulley 23 which is connected to grooved pulley 24 on shaft 25 of motor 26 by means of a belt 27.

The belt 8 conveys the bundles or pencils of fibers 5 to a chute 28 which leads them to the nip of cooperating feed rollers 29 and 31, preferably rubber covered. The feed rollers are supported in a bracket 32 attached by bolts 33 to compartment 8. The upper feed roller 29 is vertically adjustable, whereby the nip between the feed rollers may be adjusted as desired, by means of a screw bolt 34 and is locked in adjusted position by means of a nut 35. The lower feed roller 31 is positively rotated from shaft 16 by means of a sprocket wheel 36 fixed to said shaft which is connected to a sprocket wheel 37 on shaft 38 of the lower feed roller by an articulated chain 39. The lower feed roller drives the upper feed roller by means of countermeshing gears generally indicated by reference numeral 41.

The feed rollers 29 and 31 feed the bundles or pencils of fiber 5 into the path of a picker cylinder or drum comprising pins or nails 42 mounted on the surface of a drum 43 which is rotated by means of motor 26 through a grooved pulley 44 fixed to the shaft 25 of said motor, a belt 45 and a grooved pulley 46 fixed to shaft 47 of the drum 43. The drum is substantially completely enclosed in a bin 48.

In mounting the pins or nails 42 on the drum surface, the pins or nails are first fixed in rubber coated canvas belting material and the belting cemented or otherwise attached to the drum surface. The pins or nails are preferably about $1\frac{1}{4}$ inches long and spaced 1 inch apart on the rows, the rows being arranged so that there is $\frac{1}{8}$ of an inch between rows and each row offset $\frac{1}{4}$ of an inch from the other rows.

The bundles or pencils of fiber are opened and fluffed up by the rotation of the drum 43 in the bin 48. Since cellulose derivative fibers are prone to electrification engendered by the friction between the moving fibers, rotating drum 43, which preferably rotates at 400 R. P. M., and bin 48, the bin is lined with copper sheeting 49, which sheeting is grounded by wires 51 attached to the sheeting and a suitable ground. The bin is provided with a glass trap door 52 so that the interior of the bin may be visible. The trap door is attached to the bin by a piano hinge 53 and is provided with a latch handle 54.

The opened and fluffed up fibers 5 are removed from the bin 48 through a conduit 55 by means of a blower mechanism 56 which is operated by a motor 57 through a pulley and belt mechanism generally indicated by reference numeral 58. A flexible tube 59 of any desired length is provided on the output end of the blower 56 for directing the opened and fluffed up fiber into the desired receptacle.

As heretofore stated, the opened and fluffed up fibers are particularly suitable for use as a substitute for down-feathers and other fillings in

pillows, comforters, sleeping bags and the like. In Figure 3 a sleeping bag of the type to be filled with the artificial staple fibers of our invention is shown. This bag, generally indicated by reference numeral 61, comprises a series of tubes 62 each of which is separately filled with the fluffed up staple fiber. In making the sleeping bag the tubes are fixed at one end by stitching across one edge of the sleeping bag. These tubes are filled by inserting the flexible tube 59 into the closed end of the tube and then gradually withdrawing the flexible tube 59 as the fluffed up fiber fills the tube 62. Thus, the tube 62 is progressively filled in a substantially uniform manner. Preferably, a predetermined amount of fibers is placed in each tube. This predetermined amount is weighed by weighing means 7, dumped on feed belt 6 and opened and fluffed up by the fluffing means. When one tube 62 has been filled, another predetermined amount is dumped on to the feeding belt and the process of filling the tube repeated. When all of the tubes 62 of the sleeping bag have been filled, the open ends thereof are sealed by stitching or in any other suitable manner.

While any suitable artificial fibers may be employed as the filling in pillows, comforters, sleeping bags and the like, we prefer to use fibers having a basis of an organic derivative of cellulose, such as cellulose esters and cellulose ethers. Examples of cellulose esters are cellulose acetate, cellulose butyrate and cellulose propionate, while examples of cellulose ethers are ethyl cellulose and benzyl cellulose.

The length of the staple fiber employed is relatively important. While fairly satisfactory results have been achieved by employing fiber of a length of from 1 to $2\frac{1}{2}$ inches and having a denier per filament of from 3 to 12, optimum results are obtained by employing cellulose acetate staple fiber having a length of $1\frac{1}{2}$ inches and a denier per filament of 3. This fiber was found to fluff more uniformly than the other fibers and filled the fabric containers more completely, particularly in the case of comforters and sleeping bags.

The use of staple fiber prepared in accordance with the present invention has many advantages over fillings heretofore employed. For example, in the case of the use of down-feathers as a filling it is necessary to employ a down-proof cover. With the use of the fluffed up fibers of the present invention no down-proof material is necessary. It has been found that highly satisfactory coverings for comforters and sleeping bags are obtained by employing a fabric having a basis of an organic derivative of cellulose, particularly yarns made of filaments or fibers of cellulose acetate. A particularly satisfactory fabric to be used as a covering for comforters and sleeping bags is made by weaving in a taffeta weave a fabric wherein the warp yarns are 120 denier and the weft yarn 150 denier.

The opened and fluffed up artificial staple fiber of the present invention has high insulating powers, retains moisture to a lesser extent than other fibers and is not deteriorated by salt air or other atmospheric conditions.

It is to be understood that the foregoing detailed description is given merely by way of illustration and that many variations may be made therein without departing from the spirit of our invention.

Having described our invention, what we desire to secure by Letters Patent is:

1. Process for filling comforters, sleeping bags

and the like having a structure comprising a plurality of tubes, which comprises opening and fluffing up a quantity of staple fibers, having a basis of cellulose acetate, a length of 1½ inches and a denier per filament of 3, substantially sufficient to fill one of said tubes, while conducting away the electricity formed by said opening and fluffing up operation and progressively filling each tube with said quantity of opened and fluffed up staple fibers.

2. Apparatus for opening and fluffing up staple fibers, comprising a rotatable drum having a plurality of spaced metal points offset with respect to each other on the surface thereof, a housing for said drum, metal sheeting lining the interior of said drum housing, a wire for grounding said metal sheeting, means, including an endless belt, a hopper and an automatic weighing device, for feeding a predetermined quantity of staple fibers to said points, and a blower for removing the opened and fluffed up fibers from said housing.
